ABRASIVE REAMER

Anthony Oberholtz, Jr., Los Angeles, Calif.

Application December 21, 1942, Serial No. 469,590

12 Claims. (Cl. 51—184.3)

1

This invention relates to improvements in abrasive reamers of the type illustrated in United States Letters Patents 1,841,343, 1,910,658 and 1,910,659; although the teachings of the present invention may be employed with equal advantage in connection with other types of honing and reaming devices.

It contemplates more especially the provision of improved means for increasing the range of bore sizes that may be honed or reamed, and more particularly enables much smaller bores to be honed without sacrificing the large range of bores with the same tool serving the entire range.

Physical limitations in strength of blades and moving parts primarily controlled the size of the bores that could be advantageously bored or reamed with a single tool. Strength and full support of the blades is essential or at least desirable in that such is conducive to precision operation over an extended period or the life of the tool. Reduction in the diametric size of the blades without weakening the strength thereof is the limiting factor in the size range. To weaken the blade structure would, when the operator forced the enlarging adjustment too vigorously, distort the blades and the honing operations would be inaccurate, not circularly true, and unsatisfactory from a mechanical standpoint.

Rigidity of blade structure is important and to accomplish dependable, satisfactory honing operations over extended periods, increased honing size range should not be accomplished to the detriment of rigidity or accuracy. This presents a problem of combining normally offsetting features, namely, increased rigidity tends to determine minimum size limits of the honing blades. The teachings of the present invention has accomplished an increased range of honing operations without sacrificing rigidity and honing accuracy.

One object of the present invention is to provide an abrasive reamer construction in which shoes or blades of widely different diameter or size may be substituted quickly and conveniently, so that but one reamer is required for a wide size range of honing operations.

Another object is to provide an abrasive reamer construction having a diametral expansion which can be accurately and reliably gauged by a micrometer adjustment to a small fraction of a thousandth part of an inch without the latter serving as an obstruction to small size honing diameters.

Still another object is to provide an abrasive reamer, the expanding shoes or blades of which

2

are rigidly supported for substantially their entire length so that the reamer will finish a hole exactly true even under forced operations in an increased range of honing sizes.

5 A further object is to provide a reamer with a readily detachable micrometer adjustment that will not limit or define the minimum size of honing attainable with any reamer unit of wide size range.

10 A still further object is to provide an improved blade structure for an abrasive reamer that combines rigidity with overall size diminution and interchangeability with blades of standard size range.

15 Still a further object is to provide an increased length blade with a minimum honing size diameter to accomplish rigidity and increased size honing range with a reamer of single reamer unit.

Other objects and advantages will appear from 20 the following description of an illustrated embodiment of the present invention.

In the drawing:

Figure 1 is a vertical side view in elevation and partially in section of an abrasive reamer embodying features of the present invention.

25 Figure 2 is a vertical edge enlarged sectional view in elevation taken substantially along line II—II of Figure 1.

Figure 3 is an enlarged side fragmentary view 30 in elevation of the adjusting end of the reamer with the shoes or blades assembled therewith, the detachable micrometer adjusting instrumentalities being shown in dotted outline.

Figure 4 is a side sectional view of the other 35 end of one of the blades or shoes taken substantially along line IV—IV of Figure 2.

Figure 5 is a side view in elevation of the micrometer adjusting device that is detachably associated with the end of the reamer and shown 40 in dotted outline in Figure 3.

Figure 6 is an enlarged fragmentary side view 45 in elevation of the adjusting end of the reamer with one blade abrasive shown in section and the other in full outline.

Figure 7 is a section of view taken substantially along line VII—VII of Figure 2, one edge of an abrasive liner being shown unattached.

Figure 8 is a sectional view taken substantially 50 along line VIII—VIII of Figure 2.

Figure 9 is an edge view in elevation of the smaller blade size construction compared to the larger size blade construction shown in Figure 1.

Figure 10 is a plan view of the improved small size blade shown in Figure 9.

55 The structure selected for illustration is not

intended to serve as a limitation upon the scope or teachings of the invention, but is merely illustrative thereof. There may be considerable variations and adaptations of all or part of the teachings depending upon the dictates of commercial practice. The present embodiment comprises a body 10 with flat parallel sides 11 and tapered edges 12 providing a large end 13 and a small end 14 of the convergingly tapered body 10.

The small body end 14 terminates in an elongated threaded extension 15 over which a bearing sleeve 16 is disposed to extend short of its length to accommodate a retaining end nut 17 against the sleeve 16. The retaining nut 17 is somewhat larger in diameter than the bearing sleeve 16 which receives a substantially larger collar 18 thereover to freely rotate thereon against end displacement precluded by a composite fiber and steel washer 19 which is somewhat smaller than the collar 18.

To this end, the retaining nut 17 has a diametrically extending screwdriver blade receiving slot 20 therein to provide for the rotation thereof relative to the threaded extension 15.

The collar 18 has an enlarged peripheral exterior rounded shoulder 21 that is concavely end-cupped as at 22 to receive complementary end blades therein as will appear more fully hereinafter. A rectangular driving shank 23 extends from the large end 13 of the tapered body 10 to terminate in a polygonal body 24 which is adapted to be placed in a chuck constituting a part of a power turning tool, such as a portable electric drill. The polygonal body 24 has an enlarged end 25, which has a substantially rectangular socket 26 provided therein of somewhat larger size than the end of the driving shank 23 to permit a limited degree of play or pivotal movement therebetween in all directions.

The enlarged cylindrical end 25 of the polygonal driver 24 is retained in loose association with the free extremity of the driver shank 24 by means of a coupling comprising a cylindrical cap 27 that has a central bore 28 somewhat larger than the reduced shank 29 of the driver 24 and its enlarged end 25. The coupler cap 27 has an enlarged peripheral flange 30 that is complementary to the cylindrical coupler member 31 that is press fitted in the open bore 32 defined by the peripheral flange 30, thereby maintaining the driver 24 in loose association with the driver shank 23 in that the cylindrical coupler member 31 has its closed end 33 bored as at 34 for press-fitted engagement with the driver shank 23, to establish its rigid joinder therewith.

The coupler member 31 is fitted to the driver shank 23 in a position to provide a limited space 35 between the driver shank end and the bottom of the socket 26 provided in the driver end 25. This allows the driver 24 to move axially on the driver shank 23 and pivotally to a slight degree in all directions owing to the fact that the socket 26 is somewhat larger than the driver shank 23 and the enlarged driver end 25 has an exterior diameter somewhat smaller than the interior chamber 36 of the coupler member 31, so that limited universal movement is permitted between the driver shank 23 and its polygonal driver 24. This minimum limited movement is desirable owing to the fact that true honing can be accomplished even though the operator holds the driven end somewhat out of alignment with the power driver, such as a portable electric drill, as will appear more fully hereinafter.

The concavely end cupped blade receiving

socket 22 in the collar 18 is confronted by a similarly concavely cupped blade receiving socket 37 provided in a blade retaining collar 38, which has a bore 39 therethrough to receive the driver shank 23 therethrough and provide freedom of movement so that the retainer 38 will be free floating for support by a spring 40.

The spring 40 is of a standard, convolute type which envelopes the driver shank 23 between the fixed coupler member 31 and the floating blade end retainer 38 to urge the latter in the direction of the confronting blade receiving socket 22 in the collar 18.

A plurality of emery cloth supporting blades 40'-41, in this instance two, are shaped as complements of each other and the tapered body 10 for retention between the end capped sockets 22-37 through the urge of the spring 40. To this end the blades 40'-41 have arcuate projections 42-43 and 44-45 provided at their extremities to conform in curvature, size and shape with the capped sockets 22-37 for retention therein when the tapered body 10 is received in oppositely and complementally inclined grooves 46-47 provided in the confronting surfaces of the blades 40'-41 throughout the length thereof. This enables the blades 40'-41 to be seated throughout their entire length on the inclined edges 12 of the body 10 with the spring 40 normally urging them toward the collar 18 to assume their minimum diameter expansion so long as the spring 40 is unopposed except for the collar 18 and its retainer nut 17 serving as a stop therefor.

A counter urge or force applied to the collar 18 will cause the blades 40'-41 to ride along the diverging edges 12 of the tapered body 10 to effect their expansion or recession from each other, while the spring 40 is compressed to a corresponding degree. In this manner, the size of the bore to be honed can be predetermined by limiting the extent to which the collar 18 and the blades 40'-41 are displaced along the inclined body 10 in the direction of the driver 24, which is simultaneously rotated by a power instrumentality, such as a standard portable electric drill.

It should be noted that the tapered contact between the cupped socket ends 22-37 of the confronting members 18-38, respectively, serve to hold the complementary blades or shoes 40'-41 together with their tapered channels or grooves 46-47 in full contact with the tapered edges 12 of the body 10 for the entire length of the blades or shoes 40'-41. The channels or grooves 46-47 in the complementary blades 40'-41 have a close but free slidable fit against the edges 12 and flat sides 11 of the body 10.

It should be noted that the retainer end 17 on the body extension 15 serves to limit the extent to which the blades or shoes 40'-41 may be displaced along the tapered body 10, and a calibrator is provided therefor to limit the extent of displacement of the blades 40'-41 and their relative expansion to define a predetermined diametrical honing size, to which a bore will be finished by the abrasive action of abrasive sheets 48-49 that are detachably associated with the blades or shoes 40'-41. To this end, the abrasive sheets 48-49 are provided with substantially U-shaped edge re-enforcing cleats 50-51 that are clinched to the side edges of the abrasive sheets 48-49 to serve as attaching expedients therefor in conjunction with the blades or shoes 40'-41.

The cleats 50-51 tightly fit into side grooves 52-53 provided in the parallel side walls 54-55

of each of the complementary shoes 40'-41. The side grooves or channels 52-53 extend substantially for the length of the blades or shoes 40'-41 proximate to the curved or arcuate abrasive sheet supporting surfaces 56 that constitute the external operating surfaces over which the abrasive sheets 48-49 are tensioned for support. This renders the abrasive sheets 48-49 together with their cleats 50-51 removable for replacement with new abrasive sheets of corresponding size and structural characteristics.

Now, then, in order to adjust the blades 40'-41 with their abrasive reaming or honing surfaces 48-49 to the desired bore to accomplish the best results and to effect a predetermined expansion thereof to impart the desired finishing size, an elongated exteriorly knurled end bearing or manual handle sleeve 57 has one of its open extremities 58 interiorly sized as at 59 for substantially the length of the collar 18 to freely fit thereover for rotation relative thereto without any appreciable looseness or play therebetween. The internal end bore 59 of the manual handle sleeve 57 which fits over the collar 18, terminates in a peripheral shoulder 60 defined by the somewhat smaller interior bore 61 that communicates with a somewhat larger collar bore 59 to define the tubular manual handle sleeve 57.

The peripheral shoulder 60 contacts the composite thrust washer and limits the inward movement of the manual handle sleeve 57 relative to the collar 18, so that the sleeve edge 58 meets with the rounded peripheral shoulder 60 at the cupped end of the collar 18, thereby providing contact along the peripheral shoulder 60 and the open peripheral extremity 58 of the manual handle sleeve 57 with the collar 18 and its thrust washer 19.

A calibrated micrometer collar 62 is journaled on a reduced extremity 63 of the manual handle sleeve 57 for rotation relative thereto, it being retained thereon by an internal split spring 64 confined in an annular slot 65 of which complementary portions are in the confronting surfaces of the micrometer collar 62 and the sleeve extremity 63.

Consequently, the micrometer collar 62 is connected to and rotates relative to the manual handle sleeve 57. The micrometer collar 62 has an inwardly extending peripheral flange 66 at the outer extremity thereof to re-enforce the knurled peripheral edge 67 and to present a radially extending longitudinal rib 68 serving as a key disposed in a slot or keyway 69 provided in and along an elongated stop screw 70 for the entire length thereof between a reduced inward tip stop 71 and an outward enlarged knurled head 72 serving as a turning expedient for the elongated stop screw 70.

With this arrangement, the stop screw 70 rotates with the micrometer collar 62 while in threaded engagement with an inwardly projected threaded cylindrical wall 73 provided in the extreme end region 63 of the manual handle sleeve 57. A retaining or lock nut 74 threadedly engages the stop screw 70 above the micrometer collar 62 to retain it in adjusted position relative to the manual handle sleeve 57 so that the latter may be displaced with the collar 18 and blades or shoes 40'-41 a predetermined distance in the direction of the driver member 24 to compress the spring 40 until the stop screw tip 71 engages the retaining nut 17 and this limits any further displacement of the blades or shoes 40'-41 relative to the tapered hone body 10. This limits

the maximum relative recession or expansion of the blades or shoes 40'-41 and thus determines the honing diameter of the finished bore.

The micrometer collar 62 may be calibrated to any desired scale, but it is preferable, though not essential, to be graduated in .0025 inch and the pitch of the threads on the stop screw 70 and meshing threads 73 are such that one complete turn of the stop screw 70 is .005 inch. Other graduations or calibrations may be utilized, but this is preferred.

In adjusting the work to the hone, the stop screw 70 is screwed out so that the blades or shoes 40'-41 and their abrasive covers 48-49 are expanded to fill snugly the hole or bore to be honed, then the stop screw 70 is screwed in until its tip 71 will just touch the retaining nut 17 while the manual handle sleeve 57 is held against the tension of the spring 40. The hone blades 20 40'-41 with their abrasive covers 48-49 are now set to the size of the hole or bore. Thereafter, the stop screw 70 is adjusted by turning the micrometer collar 62 in one or a repeated series of steps to the desired extent to which the hole or bore is to be finished.

Assuming the hole or bore is to be enlarged .003 inch, the stop screw 70 is backed out .003 inch, and the lock nut 74 is then screwed to engage the micrometer collar 62. With the driver member 30 24 in the chuck of the power drill that is held securely in a vise, the power is started to turn the hone body 10 with its blades 40'-41 and abrasive covers 48-49. Force is then applied on the knurled manual handle sleeve 57 to expand the hone while the high speed rotation thereof gradually cuts the bore to the size by continuing the force or pressure on the sleeve 57 against or in the direction of the driver 24. The end surface 35 15 of the enlarged head 72 on the stop screw 70 can be held against the operator's body to steady the rotation while the work is held stationary in the operator's hand relative to the rotating abrasive surfaces 48-49 that are supported by the blades or shoes 40'-41. This force is continued or progressively applied until the stop screw 70 has its tip 71 in contact with the retainer nut 17. This determines the predetermined size of the honed bore.

In order to hone bores that are smaller in diameter than the manual handle sleeve 57 and the stop screw 70 preferably having an enlarged knurled head 72, the manual handle sleeve 57 is detachably associated with the collar 18 so that the hone 10 with its predetermined size of blades 50 40'-41 may be displaced through the bore of the work, and thereafter the manual handle sleeve 57 replaced with its stop screw 70 and enlarged knurled head 72 having a smooth curved surface 75 serves as a suitable stabilizing influence when 55 60 the body of the operator is held thereagainst. It should be observed that the manual handle sleeve 57 serves as a manually supported end bearing which is removably and rotatively associated with the collar 18 for unobstructed attachment and detachment therewith as part of the hone body 10 to fully accomplish the specified function and purposes therefor. For instance, this arrangement permits the manual handle sleeve 57 to be 65 70 removed in the ordinary use of the device to permit a bore of a wrist pin or a bearing comprising a part of any other structural part or device to be passed over the abrasive sheets 48-49 on the body 10 and, thereafter, the manual handle sleeve 75 77 57 is replaced on the body end or collar 18, there-

by enabling the honing of much smaller bore diameters than is otherwise possible.

So that full advantage may be acquired through the use of a detachable manual handle sleeve 57, an improved blade structure has been provided that takes care of the smaller bore diameters without requiring a smaller size hone body 10 to which rigid, thick, standard blades or shoes 40'-41 are adaptable to this end a much longer blade 76 (Figure 9) is utilized, so that the effective abrasive cover supporting length 77 from the tip 44' to the shoulder 45' can be thinned down below the limits of the required rigidity to accommodate the same channel or groove 46' therein. By thinning down the effective abrasive surface 77, smaller diameters are provided and still the same channel or groove 46' is accommodated at the expense of strength and rigidity at this portion; however, the increased length of the blade 76 provides an inoperative and appreciably heavier portion 78 between the shoulder 45' and the extreme extremity 45", which compensates in strength for the weakened reduced portion 77 that determines the minimum size bore that can be honed below that which was possible with the uniformly shaped blades or shoes 40'-41.

In the thinned down portion 77, which carries the abrasive covers 48-49, the inclined channels 46' therein approach the outer surface to an extent that an opening 79 occurs therethrough just in front of the shoulder 45', but the increased thickness of the ineffective honing portion 78 provides the necessary strength to compensate therefor and the comparative weakness of the thinned down portion 77.

It should be noted, however, the blades or shoes 76 of increased length are accommodated by the same hone body 10 owing to the fact that in the smaller diameter blades or shoes 76, the effective honing surface 77 is appreciably shorter than for the blades 40'-41 of standard and uniform thickness throughout. In the smaller diameters to be honed, the length is not an important factor and for that reason correspondingly shorter abrasive covers are provided which are constructed similar to the abrasive covers 48-49 and engage in corresponding side slots 79 provided for the effective length 77 of the blade or shoe 76.

Two complementary blades 76 of smaller shape and size, are carried by the tapered hone body 50 edges 12, and the effective honing portion 77 of the blades or shoes 76 are provided proximate to the insert end of the hone body 10 corresponding with the collar 18 which is cupped as at 22 to receive the corresponding end 44' of the blade or shoe 76.

It will thus be apparent that the combination of improved blade or shoe structures 76 for small holes or bores together with the detachable speed sleeve 57, provides a greater range of honing sizes 60 for the body 10 than was heretofore possible owing to limitations determined by the speed sleeve and its adjusting head, as well as the design of the blades or shoes 40'-41 for any given hone body 10.

It should be observed that different sizes in the uniformly shaped blades or shoes 40'-41, as well as in the irregularly shaped blades or shoes 76 for smaller hones, are provided so that a range of hole diameters or bores of appreciably larger 70 and smaller size limits can be effectively honed without requiring more than one hone body 10 and its auxiliary parts.

While I have illustrated and described a preferred embodiment of this invention, it must be 75

understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. In an adjustable abrasive hole-finishing cutting tool, the combination with a body, of a plurality of abrasive sheet supporting shoes adjustably associated with said body, actuator means interposed between said body and said shoes for expanding and contracting said shoes relative to each other, means on the end of said body for operating said actuator means, an unconnected end bearing removably and rotatively associated with said body for unobstructed operative attachment and inoperative detachment therewith to serve as a manual handle sleeve and calibrated means on said end bearing said calibrated means cooperating with said actuator means to control the expansion of said shoes to a predetermined limit from an initially set relative position.

2. In an adjustable abrasive hole-finishing cutting tool, the combination with a body, of a plurality of abrasive sheet supporting shoes adjustably associated with said body, actuator means interposed between said body and said shoes for expanding and contracting said shoes relative to each other, means on the end of said body for operating said actuator means, an unconnected end bearing removably and rotatively associated with said body for unobstructed operative attachment and inoperative detachment therewith to serve as a manual handle sleeve and calibrated means on said end bearing, said calibrated means cooperating with said actuator means to control the expansion of said shoes to a predetermined limit from an initially set relative position.

3. In an adjustable abrasive hole-finishing cutting tool, the combination with a body, of a plurality of abrasive sheet supporting shoes adjustably associated with said body, actuator means interposed between said body and said shoes for expanding and contracting said shoes relative to each other, means on the end of said body for operating said actuator means, an unconnected end bearing removably and rotatively associated with said body for unobstructed operative attachment and inoperative detachment therewith to serve as a manual handle sleeve and calibrated means on said end bearing, said calibrated means cooperating with said actuator means to control the expansion of said shoes to a predetermined limit from an initially set relative position, said last named means comprising a sleeve journaled for rotation relative to said actuator means, a graduated slip collar on said sleeve, and a stop pin adjustably connected to said sleeve through said graduated collar.

4. In an adjustable abrasive hole-finishing cutting tool, the combination with a body, of a plurality of abrasive sheet supporting shoes adjustably associated with said body, actuator means interposed between said body and said shoes for expanding and contracting said shoes relative to each other, means on the end of said body for operating said actuator means, an unconnected end bearing removably and rotatively associated with said body for unobstructed operative attachment and inoperative detachment therewith to serve as a manual handle sleeve and calibrated means on said end bearing, said calibrated means cooperating with said actuator means to control the expansion of said shoes to a predetermined limit from an initially set relative position, said end bearing comprising a sleeve journaled for rotation relative to said actuator means, a graduated slip collar on said sleeve, a stop pin adjustably connected to said sleeve through said graduated collar, and means interposed between said collar and pin to insure their connected rotation as a unit while permitting the longitudinal displacement of said pin through said collar.

4. In an adjustable abrasive hole-finishing cutting tool, the combination with a body, of a plurality of abrasive sheet supporting shoes adjustably associated with said body, actuator means interposed between said body and said shoes for

expanding and contracting said shoes relative to each other, means on the end of said body for operating said actuator means, an unconnected end bearing removably and rotatively associated with said body for unobstructed operative attachment and inoperative detachment therewith to serve as a manual handle sleeve and calibrated means on said end bearing, said calibrated means cooperating with said actuator means to control the expansion of said shoes to a predetermined limit from an initially set relative position, said end bearing comprising a sleeve journaled for rotation relative to said actuator means, a graduated slip collar on said sleeve, a stop pin threadedly connected to said sleeve through said graduated collar, and a key and key-way interposed between said collar and pin to insure their connected rotation as a unit while permitting the longitudinal displacement of said pin through said collar.

5. In a cutting tool having a central body with tapered faces and shoes provided with abrasive members fitting thereon, cupped member on said body and fitting over the ends of said shoes to retain said shoes around said body, a spring positioned upon and along said body to bear against one of said cupped members, an adjusting member threadedly engaging said body and adapted to bear against the other cupped member, and an unconnected calibrated manual hand end bearing supporting sleeve removably and rotatively associated with said adjusting member for unobstructed attachment and detachment therewith to serve as a manual handle sleeve end support and stop for said adjusting member.

6. In a cutting tool having a central body with tapered faces and shoes provided with abrasive members fitting thereon, cupped member on said body and fitting over the ends of said shoes to retain said shoes around said body, a spring positioned upon and along said body to bear against one of said cupped members, an adjusting member threadedly engaging said body and adapted to bear against the other cupped member, an unconnected calibrated manual hand end bearing supporting sleeve removably and rotatively associated with said adjusting member for unobstructed attachment and detachment therewith to serve as a manual handle sleeve end support and stop for said adjusting member, said calibrated speed sleeve including a slip collar, and a stop screw extending through said slip collar and threadedly engaging said speed sleeve.

7. In a cutting tool having a central body with tapered faces and shoes provided with abrasive members fitting thereon, cupped member on said body and fitting over the ends of said shoes to retain said shoes around said body, a spring positioned upon and along said body to bear against one of said cupped members, an adjusting member threadedly engaging said body and adapted to bear against the other cupped member, an unconnected calibrated manual hand end bearing supporting sleeve removably and rotatively associated with said adjusting member for unobstructed attachment and detachment therewith to serve as a manual handle sleeve end support and stop for said adjusting member, said calibrated speed sleeve including a slip collar, a stop screw extending through said slip collar and threadedly engaging said speed sleeve, and an enlarged finger grasping knob on said stop screw to present a body contacting surface for assisting in the support of said speed sleeve.

8. In a cutting tool having a central body with 75 abrasive sheet carrying thin portion to compen-

tapered faces and shoes provided with abrasive members fitting thereon, cupped member on said body and fitting over the ends of said shoes to retain said shoes around said body, a spring positioned upon and along said body to bear against one of said cupped members, an adjusting member threadedly engaging said body and adapted to bear against the other cupped member, an unconnected calibrated manual hand end bearing supporting sleeve removably and rotatively associated with said adjusting member for unobstructed attachment and detachment therewith to serve as a manual handle sleeve end support and stop for said adjusting member, said calibrated speed sleeve including a slip collar, a stop screw extending through said slip collar and threadedly engaging said speed sleeve, complementary means on said collar and screw to insure their combined rotation while permitting relative axial displacement therebetween.

9. In a cutting tool having a central body with tapered faces and shoes provided with abrasive members fitting thereon, cupped member on said body and fitting over the ends of said shoes to retain said shoes around said body, a spring positioned upon and along said body to bear against one of said cupped members, an adjusting member threadedly engaging said body and adapted to bear against the other cupped member, an unconnected calibrated manual hand end bearing supporting sleeve removably and rotatively associated with said adjusting member for unobstructed attachment and detachment therewith to serve as a manual handle sleeve end support and stop for said adjusting member, a polygonal driver member operatively connected to said body on the end opposite said adjusting member for rotation therewith, and a collar coupler fixed to said body to engage said driver against detachment from said body while permitting slight relative universal movement therebetween.

10. In a cutting tool having a central body with tapered faces and shoes provided with abrasive members fitting thereon, cupped member on said body and fitting over the ends of said shoes to retain said shoes around said body, a spring positioned upon and along said body to bear against one of said cupped members, an adjusting member threadedly engaging said body and adapted to bear against the other cupped member, an unconnected calibrated manual hand end bearing supporting sleeve removably and detachably associated with said adjusting member for unobstructed attachment and detachment therewith to serve as a manual handle sleeve end support and stop for said adjusting member, polygonal driver member proximate to end of said body opposite said adjusting member, complementary means on said driver member and body end to establish a driving connection between said driver member and body end while permitting their longitudinal separation, and a coupler fixed to said last named body end to embrace said complementary means for retaining said driver and body end together against separation while permitting slight relative universal movement therebetween.

11. In a cutting tool having a central body with tapered faces, and abrasive supporting shoes adjustably fitted upon said faces, said shoes having a thin abrasive sheet carrying portion sized to substantially conform with the dimensional limits of said tapered body surfaces and a substantially thicker portion beyond and contiguous to said

11

sate for the requisite overall body strength of said abrasive supporting shoes.

12. In a cutting tool having a central body with tapered faces, and abrasive supporting shoes adjustably fitted upon said faces, said shoes having a thin abrasive sheet carrying portion sized to substantially conform with the dimensional limits of said tapered body surfaces and a substantially thicker portion beyond and contiguous to said

5

12

abrasive sheet carrying thin portion, there being a tapered slot in the bottom surface of and extending for the overall length of said shoes to serve as a complement of said tapered body surfaces with the thicker shoe portion serving to compensate for the requisite overall body strength of said abrasive supporting shoes in relation to said tapered slot.

ANTHONY OBERHOLTZ, JR.
